DESIGN FOR A DRESS

William Slepin, Philadelphia, Pa.

Application November 26, 1938, Serial No. 81,401

Term of patent 3½ years

To all whom it may concern:

Be it known that I, William Slepin, a citizen of the United States and residing in the city of Philadelphia, State of Pennsylvania, have invented a new, original, and ornamental Design for a Dress, of which the following is a specification, reference being had to the accompanying drawing, forming part thereof, wherein

Fig. 1 is a front view of a dress showing my new design.

Fig. 2 is a rear view thereof.

Fig. 3 is an enlarged view of the sleeve portion of the dress shown in Figs. 1 and 2, showing my new design.

My design is characterized by the specific embroidered sleeves, as shown, in combination with the specific dress.

I claim:

The ornamental design for a dress, substantially as shown and described.

WILLIAM SLEPIN.
